[57] CLAIM

The ornamental design for a demonstrator for indicating the effect of additive in engine oil and the like, substantially as shown and described.

DESCRIPTION

FIG. 1 is an isometric view from an upper aspect of a demonstrator for indicating the effect of additive in engine oil and the like, showing my new design;
 FIG. 2 is a side elevational view thereof;
 FIG. 3 is an end elevational view thereof;
 FIG. 4 is a top plan view thereof.
